UNITED STATES PATENT OFFICE

2,100,082

HAIR CUTTING DEVICE

Joseph Mareska, Cicero, Ill.

Substitute for application Serial No. 588,061,
January 22, 1932. This application February
6, 1936, Serial No. 62,597

10 Claims. (Cl. 30—208)

The invention relates to cutters, and more particularly to clippers used in cutting hair.

This application is a substitute for my prior abandoned application Serial No. 588,061, filed January 22, 1932.

The hair clippers used in cutting hair have the objectionable feature that the strands of hair do not enter the inter-space between the cutting teeth so that a thorough cutting of the hair is difficult, if not impossible.

10 It, therefore, constitutes an object of the invention to provide means for positively forcing the hair into the cutting zone so that they are exposed to the cutting action of the teeth of a clipper.

15 A further object aims at providing a gatherer for the hair to force the hair between the cutting teeth of the clipper.

It is also an object of the invention to provide a hair gatherer which, upon actuation of the clipper, reciprocates in a direction transverse to the reciprocation of the cutting teeth, so as to positively force the hair into cutting position.

With these and other equally important objects in view which will become apparent from 25 a perusal of the invention, the latter comprises a means described in the following specification particularly pointed out in the claims forming a part thereof, and illustrated in the accompanying drawings, in which

30 Fig. 1 is a top plan view of a hair clipper to which my invention has been applied.

Fig. 2 is a side view of the improved hair clipper.

Fig. 3 is a section on the line 3—3 of Fig. 1.

35 Fig. 4 is a top plan view of an attachment employed for the retaining of an actuation of the hair gatherer.

Fig. 5 is a section on the line 5—5 of Fig. 4.

Fig. 6 is a top plan view of the gatherer.

40 Fig. 7 is a side view of the part shown in Fig. 6.

Fig. 8 is a section on the line 8—8 of Fig. 3.

Fig. 9 is a rear view of the improved hair clipper.

Fig. 10 is a section taken through the front 45 part of the clipper.

Fig. 11 is a detail view of links employed for the actuation of the gatherer.

Fig. 12 is an end view of the part shown in Fig. 11, and

50 Fig. 13 is a section on the line 13—13 of Fig. 5.

The clipper per se does not form a part of the invention, and only such parts thereof will be referred to as are necessary for an understanding of the invention.

The gatherer comprises an attachment and includes a base plate 10 which at the front end has teeth 11 and 12 constituting guide ledges which are at the end of the plate, as will be evident by reference to Fig. 4.

The base plate 10 is formed with a depressed portion 13 at the center of the plate and originating at the front edge and terminating short of the rear end. To the bottom of the depression 13 is secured a leaf spring 14 which extends toward the rear end of the plate and rises in a curved end 15 bent to form a bead or bulge 16 which serves as a guide spring for a purpose hereinafter further referred to.

The base plate 10 is formed with side walls 17 and 18 extending from the rear end of the plate to about the center thereof, and adjacent to each side wall is a column 19 and 20, respectively, which define thereupon a gap 21. To each column and at the front thereof is secured a spring 22 which extends horizontally and downwardly to be within the horizontal plane defined by the side walls 17 and 18 and overlies a cam 23 engaging the forward end of the cam.

The side walls 17 and 18 are provided on the inner side with horizontal grooves 24.

Bearings 25 and 26 are respectively secured to the columns 19 and 20 to receive therein a horizontal pin 27 which extends through a lever 28, having its lower end bifurcated as at 29 to receive therein an irregularly shaped link 30 and connected thereto by a pin 31.

The link 30 is formed intermediate its ends with a lug 32 adapted to engage a horizontal roller 33 entering columns 19 and 20.

As shown in Fig. 6, the gatherer comprises a plate 34 shaped as a comb having a plurality of teeth 35 which are constructed like arrow heads.

The plate 34 is extended into a shank 36 which is provided with downwardly extending lugs 37 which are provided with heads 38 adapted to travel in the grooves 24 in the reciprocation of the gatherer as will be hereinafter further explained.

The shank 36 is formed with a rectangular extension 39.

To the underside of the shank 36 is secured a rectangular plate 40 which is provided with a central cut-out portion 41 and terminates at the outer end in a sleeve 42 to carry therein a pin 43.

A hinge 44 is also secured to the underside of the shank 36, the leg 45 of said hinge being secured to the shank while the other leg 46 is hingedly connected to the link 30 by a pin 47. The leg 46 of the hinge 44 is provided with an upstanding member 48 terminating in a horizontal flange 55

49 directed toward the shank extension 39 and forming a stop therefor to limit the pivotal movement of the gatherer.

From the foregoing it follows that upon the 5 lever 28 being rocked that the gatherer 34 is forced to execute a reciprocating movement, and this movement is in a path predetermined by the cams 23 and the springs 22.

In other words, when the lever 28 is moved 10 so that the lower end thereof travels between the springs 22 and the upper side of the cams 23 and upon leaving contact with the springs, the pin 43 drops to continue its travel on the under-side of the cams at which time the lever 28 is on its 15 return stroke, and causes the gatherer to move backward with the front end thereof, however, in raised position until the lug 32 of the link 30 enters into engagement with the pin 33, at which time the pivotal connection 46, 47 is raised causing 20 the front end of the gatherer to be lowered. At the same time the bead 16 of the spring 14 causes the pin 43 to be placed into the upper side of the cams 23 preparatory to the ensuing movement toward the left whereupon the cycle is repeated.

The clipper per se comprises handles 50 and 51 which actuate cutters 52 and 53, it being understood that upon closing of the handles the upper cutter member 52 is moved laterally and upon release of the handles on the spring pressure, the upper cutter member moves into original position.

The reciprocation of the upper cutter member will produce a cutting action by the lower cutter member 53, as will be understood by those versed 35 in the art.

To the handle 51 is secured a plate 54 which is provided with an upright post 55 to which is pivotally secured a horizontal lever 56 provided with a central slot 57 connected at the outer end 40 to a link 58 to which is rigidly secured a lever 59, so that the lever 56, the link 58 and the lever 59 constitute a rigid system.

The outer end of the lever 59 is connected with the handle 50 by a turn buckle 60 in order to 45 adjust the distance to the outer lever end 59 with respect to the handle to vary the range of movement of the lever 56.

A horizontal link 61 underlies the lever 56 and is secured thereto by a screw 62. The link 61 is 50 bifurcated at either end and receives at the forward end a member 63 secured to the link 61 by a pin 64.

The member 63 is apertured as at 65 to receive a pin 66 at the upper end of the lever 28.

55 The bifurcated rear end of the link 61 has a horizontal pin 67 which extends through a slot 68 in the upper end of a curved lever 69 which extends through an elongated slot 70 of the plate 54.

60 The lever 69 is pivotally secured as at 71 in a pendent bearing 72 secured to the underside of the plate 54.

The plate 54 at the rear end is turned upward and then horizontally to form a horizontal guide 65 plate 73 provided with a slot 74 in which the curved lever 69 reciprocates.

From the foregoing, it is clear that upon actuation of the handle 50, the lever system 56, 58, and 59 is oscillated about the upright post 55 70 causing the link 61 to reciprocate, and this reciprocation is participated in by the lever 69 and the lever 28, which latter executes a reciprocating movement at its lower end causing reciprocation of the gatherer 34, as has been previously described.

In order to secure the gatherer and its associated parts in proper position a clipper holder member 75 is provided which is secured at 76 to the body member 77 of the clipper proper, and such holder member is extended and is secured at its ends 78, and is provided with inwardly directed lugs 79 which enter corresponding grooves in the base plate 10 as shown in Fig. 8.

From the foregoing, it is thought that the operation of the device is obvious. Upon reciprocation of the handle 50 the gatherer 34 is actuated to project forwardly and downwardly so as to become anchored with the strands of hair, and upon release or downward movement of the handle 50 the gatherer is brought back to original 15 position, delivering the strands of hair into the interspace between the cutting teeth of the cutter members 52 and 53 thus insuring effective cutting of the hair.

It is noteworthy that a screw 80 is provided 20 (Fig. 2) which adjusts the relative position between the base 10 of the gatherer and the cutting member 53, so that the cutting depth of the device may be regulated. In other words, the gatherer may be used as a gauge for predeter- 25 mining the extent to which hair is cut.

While the drawings show a preferred embodiment of the invention, numerous changes, alterations, and revisions may be made without departing from the spirit of the invention.

I, therefore, do not limit myself to the details of construction and arrangement of parts, as shown, but wish to include all changes, variations, revisions and alterations constituting departures within the scope of the invention as defined in the 35 appended claims.

I claim:

1. In combination with a pair of cutting members and their handles, a support secured to said cutting members, a gatherer carried by said support, means for reciprocating the gatherer, and means for guiding said gatherer during its reciprocation so that said gatherer moves in more than one plane relatively to said cutting members.

2. In combination with a hair cutter, an attachment secured thereto, a gatherer movably arranged in said attachment, means actuated by the hair cutter for causing said gatherer to execute a reciprocating action, and means for causing said gatherer to occupy different horizontal planes 50 during consecutive reciprocations.

3. In combination with a cutting device comprising a pair of cutter members, one of which reciprocates on the other and is provided with a handle, an attachment secured to said device, a gatherer movably arranged in said attachment, a plurality of links connecting said gatherer with the movable handle to cause reciprocation of said gatherer upon actuation of said cutting device, and means in said attachment for causing said gatherer to move in different horizontal planes during consecutive reciprocations.

4. In combination with a hair cutter, a gatherer movably supported by said cutter, means for causing reciprocation of said gatherer at right angles to the reciprocation of said hair cutter, said means being actuated by said hair cutter, and relatively slidably adjustable means for predetermining the cutting depth.

5. In combination with a pair of cutting members and their handles, a support secured to said cutting members, a gatherer carried by said support, means for guiding said gatherer during its reciprocation to move in a closed path, and means for predetermining the cutting depth.

6. In combination with a hair cutter, a gatherer movably supported by said cutter, means for causing reciprocation of said gatherer at right angles to the reciprocation of said hair cutter, said means being actuated by said hair cutter, and adjustable means for predetermining the cutting depth. 5
7. In combination with a pair of cutting members and their handles, a support secured to said cutting members, a gatherer carried by said support, means for guiding said gatherer during its reciprocation to move in a closed path, and means for predetermining the cutting depth comprising a screw for adjusting the relative position between 10

the base of the gatherer and one of the cutting members.

8. The combination as embodied in claim 1 and including adjustable means for predetermining the cutting depth. 5

9. The combination as embodied in claim 2, and including adjustable means for predetermining the cutting depth. 10

10. The combination as embodied in claim 3 and including relatively slidably adjustable means 10 for predetermining the cutting depth.

JOSEPH MARESKA.
